Primary Examiner — David Muller(74) *Attorney, Agent, or Firm* — Kirby Drake(57) **CLAIM**

The ornamental design of an insertion device, without a distal opening.

DESCRIPTION

FIG. 1: Top side perspective view of an ornamental design for an insertion device without a distal opening;

FIG. 2: Top view of an ornamental design for an insertion device without a distal opening;

FIG. 3: Bottom view of an ornamental design for an insertion device without a distal opening;

FIG. 4: Right side view thereof;

FIG. 5: Left side view thereof;

FIG. 6: First end view thereof; and,

FIG. 7: Second end view thereof.

1 Claim, 3 Drawing Sheets(56)
